Primary Examiner — John R Yeh(74) *Attorney, Agent, or Firm* — Walker Griffin Weitzel;
Alloy Patent Law(57) **CLAIM**

The ornamental design for a steam wand cleaning apparatus, as shown and described.

DESCRIPTION

FIG.1 is a perspective view of a steam wand cleaning apparatus showing my new design;

FIG.2 is a left-side view thereof;

FIG.3 is a right-side view thereof;

FIG.4 is a bottom view thereof;

FIG.5 is a top view thereof;

FIG.6 is a front view thereof; and

FIG.7 is a back view thereof.

In the drawings, the portions of the design shown in broken lines form no part of the claimed design.
